CHARLES F. ROOT, OF CLEVELAND, OHIO, ASSIGNOR TO THE CHANDLER & PRICE COMPANY, OF CLEVELAND, OHIO, A CORPORATION OF OHIO

SHEET-TRANSFERRING MECHANISM FOR PRINTING PRESSES

Application filed October 18, 1923, Serial No. 668,287. Renewed February 3, 1930.

The present improvements relate more particularly to sheet feeding and delivery mechanism adapted for use primarily with so-called Gordon or platen printing presses. One object of the invention is to provide a mechanism of the character referred to that may be readily attached to existing presses with little or no alteration in their structure and that, when attached or installed, will not unduly encumber the press or be in the way of the operator. The mechanism is designed to pick up and transfer the sheets, both in feeding the same to the platen and in subsequently removing the same therefrom, by pneumatic suction, and the invention has as a further object the control of such suction conjointly with the movement of the picker fingers or sucker tips so as to locate the sheets accurately on the platen of the press. Other features of improvement relate to the means provided for elevating the stack of blank sheets as the latter are gradually removed by the feeding mechanism, means for collecting and retaining in an orderly stack the printed sheets as they are delivered from the platen, and numerous details of construction that form part of or appertain to the sheet feeding and delivery mechanisms proper.

Claims to such delivery mechanism have been required to be divided out and are presented in my separate application filed December 9, 1930, Serial No. 501,130.

To the accomplishment of the foregoing and related ends, the invention, then, consists of the means hereinafter fully described and particularly pointed out in the claims, the annexed drawings and the following description setting forth in detail certain mechanism embodying the invention, such disclosed means constituting, however, but one of various mechanical forms in which the principle of the invention may be used.

In said annexed drawings:—

Fig. 1 is a plan view showing my improved sheet feeding and delivery mechanism as attached to a press of the type hereinbefore referred to; Fig. 2 is a front elevation of such mechanism and press; Fig. 3 is a side elevation of the same as viewed from the left in

Figs. 1 and 2; Fig. 4 is a side elevation of the sheet feeding mechanism and table whereon the blank sheets to be fed are supported, as viewed from the left in Figs. 1 and 2, the sheet delivery mechanism not appearing; Fig. 5 is a front elevation of such sheet feeding mechanism and table, the scale of such figure being somewhat larger than that of the preceding figures and the angle at which the parts are viewed being slightly different from that of Fig. 2; Fig. 6 is a plan view of such feeding mechanism and table by themselves on a scale corresponding with that of Fig. 5; Fig. 7 is a vertical section through an element of the feeding mechanism designed to preliminarily separate the topmost sheet from the stack the plane of the section being indicated by the line 7—7, Fig. 6; Fig. 8 is a section on a parallel plane of such sheet separating device, the plane of the section being indicated by the line 8—8, Fig. 6; Fig. 8a is a transverse section of one of the parts appearing in Fig. 8, as indicated by the section line 8a—8a thereon; Fig. 9 is a vertical section of the mechanism whereby such sheet separating device is supported and operated, the plane of the section being indicated by the line 9—9 on Figs. 3, 4 and 6; Fig. 10 is a vertical section of an element of the sheet feeding device, i. e., the mechanism whereby the sheet is transferred from the stack to the platen, the plane of such section being indicated by the line 10—10, Fig. 10a; Fig. 10a is a horizontal section of such element, the plane of the section being indicated by the line 10a—10a, Fig. 10; Fig. 10b is a vertical section of such element at right angles to the plane of Fig. 10, as indicated by the line 10b—10b thereon; Fig. 11 is a vertical section through another element of such sheet feeding device, the plane of the section being indicated by the line 11—11, Fig. 6; Fig. 12 is a similar section through still another element, the plane of the section being indicated by the line 12—12, Fig. 6; Fig. 12a is a section of the detail at right angles to that of Fig. 12, as indicated by the line a—a of Fig. 6; Figs. 13, 14 and 15 are vertical sections of different portions of the horizontally extending arm whereby the sheet feeding

device is supported, the planes of such sections being indicated on Fig. 6 by the lines 13—13, 14—14 and 15—15, respectively; Fig. 16 is a vertical section through one of a plurality of similar valves provided for controlling the air suction on the sheet separating, sheet feeding and sheet delivery devices, respectively, the plane of the section being indicated by the line 16—16, Fig. 2; Fig. 17 is a vertical central section through an air blast device associated with the feed table and sheet separating device, the plane of the section of said figure being indicated by the line 17—17 on Fig. 4; Fig. 18 is an elevation of the upper portion of such air blast device, as viewed from the left in Fig. 17; Fig. 19 is a horizontal section through a valve detail in the air connection to such air blast device, the plane of the section being indicated by the line 19—19, Fig. 3; Fig. 20 is a horizontal section of the feed table support and of the mechanism for automatically raising such table, the plane of the section being indicated by the line 20—20, Figs. 2 and 3; Fig. 21 is a vertical section and elevation of a detail of such table elevating mechanism; Fig. 22 is a side elevation of the sheet delivery mechanism, as viewed from the left in Figs. 1 and 2, it being noted that such mechanism is attached to the right side of the press just as the sheet feeding mechanism is attached to the left; Fig. 23 is a top plan view of the receiving table to which the sheets are transferred by such delivery mechanism from the platen; Fig. 24 is a plan view showing a detail of the construction of such table; Fig. 25 is a vertical section through such detail, the plane of the section being indicated by the broken line 25 on Fig. 24; Fig. 26 separately illustrates in plan another portion of the detail in question; Fig. 27 is a vertical section showing another constructional detail of the table, the plane of the section being indicated by the line 27—27, Fig. 23; and Figs. 28, 29, 30 and 31, respectively, illustrate in more or less diagrammatic fashion the operation of the sheet separating device preliminarily to the transfer of a sheet from the stack to the platen by the sheet feeding device.

The press illustrated in the drawings and more particularly in Figs. 1 and 2, only certain portions of such press appearing as necessary in the remaining figures, is of the familiar platen or Gordon type and need not be further described than to note the oscillatorily mounted platen 1 on which the sheet requires to be placed preliminarily to being brought into contact with the form by the conjoint movement of such platen and of the opposite bed 2 which carries such form in a suitable chase. Of the driving mechanism of the press, only the so-called large gear 3, carried by shaft 4, is of interest herein, this gear being utilized as the source of power for the oper-

ation of the sheet feeding and delivery mechanism. In those figures, viz., 1, 2 and 3, wherein the press is most fully shown, the assumed position of parts is that wherein the form is thus in contact with the sheet on the platen. At this stage in the operation of the press the platen is inclined only slightly from the vertical, but, as is well known, in its sheet receiving position it is rocked into substantially horizontal position, as indicated in dotted outline in Fig. 5. It is while the platen is in such last mentioned position that the previously printed sheet thereon requires to be removed or delivered from the press and a fresh blank sheet placed in position on such platen. The time interval for accomplishing these last described operations is necessarily brief and it is of course essential that there be no interference between the sheet that is being delivered and the fresh sheet that is being thus placed on the platen. Furthermore, the sheet feeding and delivery devices must be so located and moved with respect to the platen and other operative parts of the press as not to interfere with or be caught thereby. A further consideration is that in order to observe the operation of the press and secure ready access to the platen, the space in front of the press must not be obstructed any more than where the press is being fed by hand.

With the last mentioned object in view, as well as to facilitate the operation of the sheet feeding and delivery devices without interfering with each other, I place such devices on opposite sides of the press. Each device comprises a vertical support disposed laterally adjacent to the platen and a table for the stack of sheets, (either the diminishing stack, from which blank sheets are fed to the platen, or the growing stack onto which printed sheets are delivered from the platen), that while located adjacent to the corresponding support, lies beyond the same with reference to said platen, so that approach to the latter is left substantially wholly unobstructed.

While the sheet feeding and delivery devices, as just pointed out, require to be operated in close unison and certain portions of the combined mechanism co-operate directly with both devices, it will be a matter of convenience in description to detail the construction of such devices separately, including along therewith of course the corresponding tables, the operation of which is of necessity interrelated with that of the associated device.

The member, which constitutes the main supporting element of the sheet feeding device, consists of a tubular shaft or column 5 that is rotatably supported in suitable bearings 6 attached to the left side frame of the press. The upper of these bearings is shown as being thus attached directly to such side frame, while the lower, along with the various operative parts now to be described, is carried by supplemental frames or plates 7 and 8

that are adapted to be bolted against the lower portion of such side frame. Said tubular shaft 5, as a matter of fact, is not directly mounted in the bearings 6, just referred to, but 5 lies within a telescoping tube 10 that is, in addition to being rotatable in such bearings, capable of vertically reciprocal movement therein as well. This outer tube 10 terminates short of the upper end of the inner tube 10 5 and the latter likewise extends downwardly beyond said outer tube.

Fixedly mounted on the upper end of said tubular shaft 5 is a cap piece 11 provided with a radially projecting arm 12 that terminates 15 in a horizontal angularly related tubular portion 13 (see Figs. 1, 4 and 6). Rotatably adjustably held in such tubular portion of the cap piece is a tubular extension or hollow shaft 14 and rotatably 20 mounted in turn in such tubular portion 13 and extension 14 is an inner tubular shaft 15, the respective ends of the latter projecting beyond said extension 14 in the one case and beyond such arm portion 13 in the other 25 (see Fig. 14). A hollow arm 16 is clamped or otherwise fixedly secured to the end of said inner tubular member 15 which thus projects beyond the tubular support 14, said arm lying at right angles to said member and having 30 oscillatory mounted in a cross-head bearing 16a at its extremity a tubular shaft 17.

As shown in Fig. 15, the vertical tubular shaft 5 is closed off or sealed at its upper end 35 but has a lateral opening 18 that communicates with a passage 19 in the arm or bracket 20 and tubular member 10 has an opening 20 aligned with such passage 19 and of such form as to insure communication between the 40 passage and the hollow interior of the member, irrespective of any oscillatory movement of the latter. An opening 21 of similar character in the transverse tubular shaft 17 insures communication at all times between 45 the interior of the latter and the passage in the hollow arm 16.

The suction tips or fingers 25, shown as two in number, form the lower ends of tubular members 26, the bodies 27 of which are adjustably slidably mounted on a bar 28, being secured in desired position thereon by means of clamp screws 29. Said bar is preferably hollow (for the sake of lightness) and of square or equivalent polygonal cross-section, 50 as shown in Fig. 10, and it is supported below and in substantially rectangular relation to the arm 16 by means of a slide 30 to which it is fixedly attached, as shown in Figs. 5 and 6, such slide being longitudinally movable 55 along an arm 31 that is clamped or otherwise fixedly secured at one end to the tubular shaft 17 in the cross-head bearing 16a at the outer end of tubular arm 16. Short pieces 32 of rubber hose or equivalent flexible tubing 60 connect said tubular shaft 17 either directly

with the tubes 26 that carry sucker tips 25, as shown in Figs. 1 to 6, inclusive, or preferably with coupling members 33 on the bodies 27 from which depend such tubes 26, as shown in Figs. 10, 10a and 10b. In the case 70 of such modified construction, said coupling members 33 are oscillatorily attached to the bodies 27 so that their angular relation thereto may vary as arm 31 changes in its angular relation to arm 16. It will be understood of course that shaft 17 is closed at both ends and that the only communication with the interior of such shaft and thus with the passages connecting therewith is by way of tubes 32 and 26 to the suction tips 25.

Fixedly secured to shaft 17 adjacent one end of bearing 16a is a short lever arm 35 that is connected by means of a link 36 with another lever arm 37, similarly fixedly secured to the outer end of tubular support 14, 85 wherein shaft 15 is journaled, as hereinbefore described. The inner end of shaft 15 is provided with a lever arm 38 that is connected by means of a link 39 with the vertically reciprocal outer tubular shaft 10 that forms 90 part of the vertical support whereon the sheet feeding mechanism being described is mounted. Reciprocation of said shaft 10, it accordingly follows, will serve to rock tubular shaft 15 and thereby to oscillate tubular 95 arm 16, in the free or outer end of which is journaled the shaft 17. The latter, however, being connected by means of the links and lever just referred to, will have imparted thereto an independent oscillation, the 100 amount of which is determined by the relative lengths and angular relation of said levers. The arm 31 being fixedly secured to shaft 17, as aforesaid, will partake of the latter's independent oscillatory movement and due to the fact that it extends reversely from its 105 own axis of oscillation towards the axis of oscillation of arm 16, a jack-knife action results. In other words, when the left end of arm 16 is depressed, viewing same as shown in Fig. 5 for example, the right end of said arm 31 will be depressed at an increased rate and the same is true upon reverse movement of arm 16.

The slide 30 on arm 31, from which the 115 sucker tips are supported, is connected by means of a link 40 with a bracket 41 that is clamped or otherwise fixedly secured to the cross-head bearing 16a at the outer end of arm 16, in which bearing tubular shaft 17 is 120 journaled as aforesaid. As best shown in Fig. 5, said bracket is formed with an arcuate slot 42, the center line of which intersects the axis of said shaft 17, and the corresponding end of said link 40 may be pivotally secured in any desired position in said slot by means of a clamp screw 43 or like device. When, as shown in Fig. 5, such link end is thus secured to bracket 40 in co-axial alignment with said shaft, there will be no movement of slide 30 125 130

along arm 31 incidentally to oscillation of shaft 17. However, upon shifting the point of attachment of such link end towards one end or the other of slot 42, a differential movement will be imparted to the slide whenever the shaft is oscillated by reason of the eccentric relation which such link end then occupies with respect to the axis of said shaft 17.

In the position of parts shown in Fig. 5, where the sheet feeding device is poised over the feed table preliminarily to the presentation to the sucker tips of a sheet from such table, the arcuate slot 42 in bracket 41 is designed to be concentric with respect to the point of pivotal attachment of link 40 with slide 30. Accordingly, there will be no movement of said slide incidentally to the dropping of the sucker tips or the raising thereof while the device is in the position referred to. There is likewise no such shifting movement of the slide incidentally to the transfer of the sheet to the platen, i. e., incidentally to the movement of the sheet feeding device from the position shown in full lines in said figure to that shown in dotted outline, where, as there illustrated, the clamp screw 43 that secures the outer end of said link to such slot is co-axial with tubular shaft 17. However, if the point of attachment lies to one side or the other of such coaxial position, then the rocking of the shaft will either draw the slide towards the tube or move it away therefrom as the device moves to such dotted, sheet-depositing position. As a result of the foregoing construction it will be seen that the sucker tips always start from a predetermined position or line on the table and so are adapted to pick up successive sheets from the stack resting on such table at a predetermined distance from the corresponding edge thereof. However, as the sheet is thereupon transferred to the platen the sucker tips may be shifted so as to carry such sheet a greater or less distance than that through which the device as a whole is moved incidentally to the oscillation of its support about the vertical axis defined by telescoping shafts 5 and 10.

I thus do away with any necessity for shifting the location of the stack of blank sheets since by the adjustment in question such sheets may be delivered at any desired position, within limits, longitudinally of the platen, i. e., with respect to the median line thereof. Otherwise stated, the sheet will be deposited on the platen with its forward edge in contact with the usual gauge pins exactly where it is to rest during the subsequent printing operation. Transverse alignment of the sheet on the platen is secured by properly locating the stack of sheets on the table transversely of the sheet feeding device, as will be readily understood. In order, however, to take care of a varying thickness in

the pad with which the platen is provided, or, in other words, to bring the sucker tips into a plane over such platen removed just the proper distance therefrom to deposit the sheet and allow necessary clearance for the return movement of the tips and to avoid undue pressure thereof against the platen pad, the additional adjustment shown in Fig. 12a is provided. This adjustment consists of an eccentric bearing 45 in the pivotal connection at one end of the carrier link 36 which is adapted to vary slightly the angular relation of lever arms 35 and 37. A clamp nut 46 serves to secure such bearing in selected position, this position being readily ascertained by swinging the device over the platen and allowing the sucker tips to drop thereon, and then raising or lowering the same slightly by rotating such bearing before it is locked to the lever arm 37.

The feed table consists primarily of a flat, horizontally disposed plate 50, preferably of rectangular form as shown (Figs. 1 and 6) that, as previously indicated, is located adjacent to the vertical telescoping shafts 5 and 10, whereby the sheet feeding device is supported and operated, and beyond such shafts with reference to the platen. The median line of the table may incline inwardly at a slight angle, as shown, to the median line of the platen or press but should leave the approach to the platen substantially unobstructed for the reason hereinbefore explained. The horizontally extending tubular arm 14, by which the sheet feeding device proper is carried, will lie parallel with such median line of the table when such device is positioned to pick up a sheet from the table, and the arcuate path of movement of such support and thus of the device from the position in question, shown in full lines in Fig. 6, to the sheet-depositing position, shown in dotted outline in the same figure, will of course be decreased by the amount of such angle of inclination of the median line of the table to that of the platen.

The table 50 is carried on the upper end of a shaft 51 that is vertically movable in a tubular housing 52 fixedly attached to the plate 8 that forms one of the frame elements whereby the sheet feeding mechanism is secured to the adjacent side frame of the press. Said housing also serves as a support for the table elevating mechanism, which includes a rack 53 directly cut or otherwise fixed to one side of shaft 51 and a pinion 54 that meshes with said rack, said pinion being mounted on a transverse spindle 55 journaled in suitable bearings in said housing 52. Freely rotatably mounted on the forwardly projecting end of said spindle, as best shown in Fig. 20, is a worm gear 56 that is adapted to be normally clutched to said spindle by means of a disk 57 keyed on the latter and having limited longitudinal movement with

respect thereto, the outer face of said gear being formed with a circular series of holes 58 and the juxtaposed face of said disk being provided with one or more pins 59 adapted to enter selected ones of said holes. The disk is provided with a knurled handle 60 whereby it may be pulled longitudinally outwardly against a compression spring 61 so as to disengage such pin or pins from the holes in the gear and thereupon by rotation of said handle the spindle 55 may be rotated independently of the gear to raise or lower the shaft 51, and thus the table, in order to initially adjust the vertical position of the latter.

15 Journalled in suitable bearings 62 attached to or forming a part of the housing 52 is a second spindle 63 that lies at right angles to spindle 55 and directly below the same, such spindle carrying a worm 64 that meshes with worm gear 56 and is adapted, when the latter is clutched to said spindle 55 through the medium of clutch plate 57, to rotate said last mentioned spindle and thus actuate shaft 51. Said spindle at its inner or right-hand end, as viewed in Fig. 2, is equipped with a knurled handle 65 by means of which it may be manually rotated when desired, but normally rotation thereof is designed to be secured through automatically controlled mechanism driven by the press, the portion of such mechanism immediately associated with the spindle consisting of a ratchet wheel 66 and a pawl 67 that is pivotally attached to one arm of a pawl carrier 68 oscillately mounted on said spindle adjacent such ratchet wheel. The disposition of such pawl and of the teeth on the ratchet wheel is such that the former is adapted to operatively engage the latter upon oscillatory movement in a clockwise direction, as viewed in Fig. 4, such movement being derived from a lever 70 oscillately mounted on a shaft 71, such lever being connected by means of a link 72 with a second arm on the pawl carrier 68.

20 The manner in which the lever 70 is periodically oscillated upon shaft 71 will be described later in connection with the general description of the driving connections between the various parts of the feeding mechanism and the press. However, such oscillation of the shaft and consequent oscillation of the pawl carrier does not necessarily result in actuation of the table elevating mechanism just described above. In other words, engagement of the pawl 67 with the ratchet wheel 66 is controlled by the absolute height of the upper surface of the stack of blank sheets resting on the table 50, so that the table will only be elevated as necessary to maintain such surface at the proper elevation and thereby present the topmost sheet on the stack in position to be picked up by the sucker tips 25 of the sheet feeding device. 25 Such control of the table elevating mecha-

nism is derived through a separate device associated with the table whereby the topmost sheet of the stack resting thereon is separated from such stack preliminarily to being thus picked up by such sucker tips. 70 This sheet separating device will accordingly be described next.

As best shown in Figs. 5 and 6, a frame 75, lying adjacent and substantially parallel with the rear edge of table 50, is oscillately supported at its one end about a pivotal axis 76 in a bracket arm 77 that projects from a fixed tubular support 78 located intermediately between the vertical telescoping shafts 5 and 10 and the shaft 51 whereon the table is supported. Said frame 75 lies entirely clear of the table but carries at its forward end a transversely disposed rod or bar 79, preferably of square or other polygonal cross-section, that extends longitudinally of the table. Such bar in fact lies adjacent to and parallel with the side of the table that is directed towards the platen and extends substantially entirely across the table in the direction indicated. The end of such bar adjacent frame 75 is oscillately secured thereto about an axis parallel with the axis 76 of said frame by being attached in offset relation to a short spindle 80 journaled in such frame end. A coil spring 81, connected with said spindle 80 and with the frame, tends normally to rotate the spindle and thus to rock the bar 79 in a clockwise direction, as viewed in Fig. 9.

Depending from the inner end of the spindle and attached to the corresponding end of the bar is a lever arm 85 that is equipped at its lower end with a roller 86, as best shown in Figs. 3 and 4, and mounted on the bracket 6, wherein telescoping shafts 5 and 10 are journaled, or to other fixed point, is a cam 87 that is so disposed as to engage said roller and prevent or control rotative movement of the spindle, and thus oscillation of the bar 79, upon oscillation of frame 75 and resultant bodily vertical movement of said bar. The contour of the cam 87 and its location is such as normally to retain the bar in substantially unchanged rotative position with relation to the plane of the table, but said bar is nevertheless left free to be rotated or oscillated about the axis of spindle 80 in a counter-clockwise direction by special means therefore provided.

20 Vertically reciprocably held in the tubular support to which frame 75 is oscillately attached is a plunger 90. Such plunger is provided at its upper end with a transversely extending plate 91 wherewith the lower end of a set screw 92, that is mounted in the frame at a point intermediate of its ends, is adapted to contact. The normal angular relation of the frame to such plate, and thus to the plunger 90, may be varied by rotating such set screw, as will be readily understood, a 130

lock nut 93 serving to secure the set screw in desired position. It will be noted that by reason of the character of the connection just described, reciprocation of the plunger is effective only to raise the frame 75 or to oscillate same upwardly about its axis 76, the downward movement of the frame being under gravity. As will be explained later, such downward movement in operation is limited by the height of the upper surface of the stack of blank sheets resting on table 50.

A bracket 95, adjustably clamped to vertical tubular shaft 5, carries an arm 96 that is angularly adjustable about an axis parallel with that of said shaft and is equipped with a horizontally disposed roller 97. By properly adjusting the angular position of the bracket and of such roller arm 96, the roller 97 is caused to strike against the lever arm 85 that depends from the inner end of bar 79 and thereby swing such arm in a counter-clockwise direction, as viewed in Fig. 5, the roller 86 on the lower end of such arm being temporarily swung clear of stationary cam 87 wherewith it normally contacts. As a result of the action of said roller arm 96, the bar 79 will be oscillated in the same counter-clockwise direction and this oscillation, it will further be noted, may be correlated as desired with the oscillation of the horizontally extending tubular support that serves as a carrier for the sheet feeding device, such support being mounted on the upper end of the same shaft 5 to which said arm 96 is clamped.

The lower end of plunger 90 is pivotally connected with the outer end of a lever 100 that is oscillatorily mounted on the same shaft 40 71 that constitutes the pivotal axis of pawl actuating lever 70. Angularly adjustably secured to such inner end of lever 100 is an arm 101 that constitutes along therewith in effect a bell crank, such arm extending upwardly 45 and inwardly into position to strike on occasion a lug 102 on a counter-weighted lever 103. The counterweight 104 on such lever serves merely to maintain the latter with the operative parts, that are connected with its forward end, in normal balanced condition. These parts include, as best shown in Figs. 2 and 4, a member 105 in the form of a bell crank oscillatorily mounted on an axis 106 below ratchet wheels 66. The horizontally extending 55 55 ing arm of such member is counterweighted so as normally to cause the transversely slotted upper end 107 of said member to project across into the path of the trailing end of pawl 67 which, as heretofore explained, serves 60 to actuate said ratchet wheel, with the result that the pawl is kept from engaging the teeth of the ratchet wheel and so moves idly back and forth. When, however, the weighted arm of said member 105 is raised, such slotted end 65 107 will be moved out of the path of the pawl

and the latter thus left free to engage and rotate the ratchet wheel through one or more part revolutions. A pin 108, fixed in an adjacent portion of the frame, lies in the slot in such end 107 and so serves to limit the oscillatory movement of the member in question.

The counterbalancing of the parts last described, including plunger 90 and levers 100 and 101 directly associated therewith, is such that unless the weight of frame 75 is allowed to bear on the plate 91, attached to the upper end of said plunger 90, the counterweighted bell crank member 105 will remain with its upper end in position to prevent effective operation of the pawl 67. However, it will be noted that the plunger is free to be moved upwardly without disturbing the operative connections between same and said member 105, such upward actuation being derived from a disk cam 110 mounted on a shaft 111 that contacts with a roller 112 on lever arm 100 intermediately of its ends.

Said shaft 111, it may be noted at this point, constitutes the driving means for all of the moving parts of the sheet feeding mechanism as well as of the sheet delivery mechanism, being journaled in suitable bearings 112 in the lower front portion of the main frame of the press and connected by means of gears 113 with the large gear 3 of the press (see Fig. 2). A suitable clutch 114 is desirably interposed between such gears and the shaft so that the press may be run independently of the sheet feeding and delivery mechanism when desired.

For the purpose of oscillating the two telescoping vertical tubular shafts 5 and 10 whereby the sheet feeding mechanism is supported and operated, as well as for reciprocating said shaft 10, as required in such operation, the following connections are provided between said shafts and drive shaft 111 just referred to, viz:—Near its lower end, adjacent one of the bearings 6, the inner tubular shaft 5 is provided with a pinion 115 that meshes with a horizontally reciprocable rack bar 116 carried by two links 117 attached to the frame at suitable points. The forward end of said rack bar is provided with a roller 118 that is held in contact with a disk cam 119 on shaft 111 and having the contour best shown in Fig. 3, by means of a tension spring 120 that is connected at one end with an arm radially projecting from the lower end of said shaft 5 and at its other end to a fixed point on the frame. Similarly near its lower end the outer shaft 10 is provided with a circumferentially grooved collar 125, wherewith engages one end of a bell crank lever 126, pivotally attached at its axis of oscillation to the frame, the other end of said lever carrying a roller 127 that is held in contact by the weight of said tubular shaft 10 with another disk cam 128 on shaft 111.

As a result of the foregoing construction

it will be seen that rotation of shaft 111 will be effective to oscillate the inner vertical tubular shaft 5 at predetermined times and simultaneously to raise and lower the outer tubular shaft 10. The two shafts 5 and 10 are held against relative rotative movement, incidentally to the foregoing, by means of a depending pin 129 secured to the cap 11 on said shaft 5 in parallel relation to said shaft, such pin engaging a radial slot in a laterally projecting lug 130 on the upper end of the outer tubular shaft 10. This connection, however, obviously permits relative longitudinal movement of the two shafts.

As already pointed out, rotation of drive shaft 111 serves, through engagement of cam 110 thereon with roller 112 on lever 100, to raise plunger 90 at stated intervals and oscillation of pawl-actuating lever 70 is derived from still another cam 131 on said shaft 111, such cam engaging with a roller 132 on a lever 133 that constitutes in effect a downward prolongation of lever 70.

Returning to the sheet separating mechanism which is carried by oscillatory frame 75, it will be noted that a series (three, as shown, Fig. 6) of sucker tips 135 is carried by such bar, these tips being of the special form and construction shown in detail in Figs. 7, 8 and 8a. Each, in other words, comprises a body 136 that is adapted to be clamped to the bar 79 in adjusted desired position therealong. Immediately below such body is incorporated a bushing 137 that is provided at one end with an extension 138, wherewith a section of hose 139 or equivalent flexible tubing may be attached, such bushing interiorly communicating with a chamber 140 in the sucker tip proper, such chamber being formed with an elongated slot-like opening 141. The sucker tips 135, and thus the slot-like openings 141 therein, lie transversely of the supporting bar 79 and accordingly are so located with respect to the table 50 as to lie at right angles and closely adjacent to the corresponding edge of a stack of sheets resting on such table. The tubes 139 lead to a suction manifold 142 supported adjacent the opposite edge of the table, preferably by means of a vertical tube 143 that is adjustably clamped in a bracket arm 144 so that it may be raised or lowered as well as adjusted angularly, should occasion arise. The manner in which suction is applied through such pipe 143 and manifold 142 to the suction tips 135, as well as the timing thereof, will be explained later in connection with the description of the general operation of the mechanism. However, it may be noted at this point that when the suction tips 135 are resting on top of a stack of sheets on table 50 they will, if the upper level of such stack be sufficiently elevated, serve to support the bar 79 and thus oscillatory frame 75 without the plate 91, carried by vertically

reciprocable plunger 90, necessarily contacting with set screw 92. In other words, under the conditions stated, said plunger will be effective only to raise oscillatory frame 75 and with it bar 79 and the sucker tips carried thereby, and thereupon to drop the same until such sucker tips rest on the stack. In such case further downward movement of the plunger, unassisted by the weight of oscillatory frame 75 and attached parts, will, as previously described, be ineffective to release pawl 67 from the shrouding action of member 105. On the other hand, whenever, due to removal of successive sheets from the top of the stack, the level of the latter falls sufficiently so that oscillatory frame 75 bears sufficiently on plunger 90 to cause lever 101 to kick such shroud element out of the way of the pawl, the latter will begin to raise the table and thus the top level of the stack until the previous condition again obtains.

Associated with the sheet separating device just described is an air blast device, shown in detail in Fig. 17, the function of which is to assist the sucker tips 135 to separate the top-most sheet from the rest of the stack and to prevent separation of more than such one sheet and the picking up thereof by the sucker tips of the sheet feeding device. This device comprises essentially a tubular air nozzle 150 that is formed with a narrow, vertically disposed, discharge orifice 151, such nozzle being suitably supported so as to lie immediately in front of the stack of sheets on table 50 (see Fig. 5) at approximately the same level as the top of such stack and preferably midway between the ends of the stack as regarded from the side in question. Such side of the stack is maintained in proper vertical alignment by means of two angular, vertically upstanding guides 152, adjustably secured to a transverse supporting plate 153 by means of clamp screws 154 and the same plate 153, or rather the bracket 153a, to which such plate is in turn attached, serves as a convenient means of support for the air blast device, including nozzle 150 referred to. To this end such nozzle is attached in rectangular relation to the upper end of a vertical tube 155 that is oscillatorily supported about a transverse axis formed by a pin or stud 156 journaled in a forwardly projecting lug 157 on said bracket 153a. Associated with the pin is a clamp 158 whereby the tube 155, and therewith the nozzle 150, may be raised or lowered. At a point just below the nozzle said tube is formed with a series of apertures 159 and a telescoping sleeve 160, slidably mounted on the tube and provided with a corresponding series of apertures 161, is adapted either to close such first-named apertures or leave the same partially or wholly open as desired, thereby graduating the blast of air delivered through the nozzle 150 to suit individual conditions encountered in the stack.

Air is supplied under suitable pressure to tube 155 by means of a hose connection 162 secured to said tube near the lower end thereof.

- 5 The air line through which air is thus supplied includes, in addition to a section of hose or flexible tubing 163, that is attached to said connection 162, a horizontally extending pipe section 164 (see Fig. 3) that lies some distance above shaft 111 and is provided with a series of vent openings 165, as best shown in Fig. 19. These openings 165 are adapted to be alternately opened and closed by means of a sleeve 166 slidably fitted to such pipe section and formed with openings 167 adapted to register with said openings 165. One of the links 117, by means of which the rack bar 116 is carried, is provided with an upward extension 168 that has a loose connection 119 as by pin and slot with said sleeve, whereby oscillation of said lever is effective to reciprocate the latter. When the openings 167 register with the openings 165, no effective pressure will be transmitted to the line beyond and thus to nozzle 150; in other words, the latter will deliver a blast of air against the stack of sheets on table 50 only when the sleeve 166 is moved to close the openings 165.
- 20 Carried by nozzle 150 with its bristles directed in the same direction as the discharge opening 151 in said nozzle is a small rectangular brush 170 (Figs. 3, 5 and 17). By vertical adjustment of tube 155 the nozzle with such brush is brought to an elevation corresponding with the top of the stack of sheets on table 50 and when such tube is rocked inwardly, i. e., towards the stack, the bristles of the brush are intended to graze the edges 25 of the uppermost sheets on such stack. Such inward rocking movement of the tube, and thus of the brush, is induced by a tension spring 171 attached at one end to the tube above its pivotal axis 156 and at its other end to plate 153, or any equivalent means, a set screw 172 in the opposed face of such plate or bracket 153a serving as an adjustable stop to limit such inward movement, so that the brush will press against the edges of the 30 sheets composing the stack with just the right amount of pressure and no more. The rocking movement of the tube in the opposite direction, i. e., to swing the brush out of contact with the sheets, is derived from a cam extension 173 secured to the upper end of pawl-actuating lever 70, such cam being disposed to engage a downwardly projecting roller 174 on an arm 175 that is adjustably secured to the lower end of tube 155. This roller is long enough to take care of any longitudinal adjustment of the tube in its oscillatory mounting and the cam 173 is so formed (see Fig. 20) that every time the lever 70 moves rearwardly, the roller 174 will be displaced

inwardly and thereby swing the upper end of the tube with brush 170 outwardly.

As previously stated, the sheet delivery device is located on the opposite side of the press from the sheet feeding mechanism which includes the sheet feeding device proper, the sheet separating device and the table with its elevating mechanism hereinbefore described. Such delivery device (see Figs. 1, 2 and 22) comprises primarily a radially projecting tubular arm 180 of telescoping construction that is carried at the upper end of a vertical tubular shaft 181, being secured in desired angular adjustment about the axis of said shaft by means of a suitable clamp 182. The interior of said arm communicates freely with the interior of such shaft and similarly angularly adjustably secured to the free end of said arm is a tubular extension 183 that is provided with two or more integral sucker tips 184. Such extension is adapted to be angularly adjusted about its own axis and the point of attachment thereof to the outer extremity of arm 180 may furthermore be vertically adjusted, as need not be described in detail.

The adjustment of the several parts just described is designed to be such that when the shaft 181 is swung inwardly, i. e., in a clockwise direction as viewed in Fig. 1, to a predetermined limiting position and then lowered, the sucker tips 184 on tubular arm extension 183 will be brought into contact with a sheet on the platen in the open position of the latter, this being the same position occupied by the platen when it receives a fresh sheet to be printed. Suction being applied through tubular shaft 181, arm 180 and such extension 183 of the latter, the sheet thus in contact with the suction tips will be picked up by the latter and by a compound raising and swinging movement of shaft 181 in a direction the reverse of that just referred to, such sheet will be carried in a counter-clockwise direction across large gear 3 of the press into position to be dropped onto a table 185 provided for the purpose. This table is omitted from Fig. 1 in order not to obscure the underlying parts, but as shown in Figs. 2 and 22, it is carried by a hollow shield 185a of outwardly curved or rounded contour that is attached to the adjacent side frame of the press and serves to cover the adjacent upper portion of large gear 3 so as to keep the sheet from coming in contact with the latter. Said sheet receiving table preferably inclines upwardly and outwardly, as shown in Fig. 2, and in connection therewith means are provided to align the successive sheets with those previously deposited so as to form a compact stack thereof. These means, as illustrated in detail in Figs. 23 to 27, inclusive, include an inner guide 186 in the form of a longitudinally extending plate that is adjustably

attached to the latter, being carried by a flat bar 187 set flush in the top of the plate and provided with a set screw 188, whereby said bar may be fixed in place with the guide 186 located approximately in alignment with the corresponding edge of the successive sheets as deposited by the delivery device. In addition to such guide plate 186, the position of which will not be changed for a given setting of the mechanism, three other relatively movable guides 190 are mounted on the plate 185, each being adjustably attached by means of a clamp 191 to a bar or rod 192. As clearly shown in Fig. 23, two of said rods lie in parallel relation to the inner guide plate 186 but extend in opposite directions from a transverse median line on said plate, while the third rod 192 lies substantially on such median line, or in other words at right angles to the inner guide plate 186. The outer ends of said rods are suitably guided in apertured lugs 193 on the corresponding edges of the plate, while their inner ends have a loose pivotal connection, as shown in Figs. 24 and 25, with an oscillatory disk 194 suitably secured to the table below the surface thereof. Rectilinear movement of the rods 192 is insured by means of pins 195 on the inner ends thereof that are guided in slots 196 formed in a plate 197, the same pins engaging approximately radial slots 198 in disk 194 to form the pivotal connection just referred to. The disk is provided with a downwardly projecting central stud 199 to which is attached a lever arm 200 that is in turn connected by means of a link 201 with an operating arm 202 on the same tubular shaft 181 that carries the sheet delivery device. A coil spring 203 surrounds stud 199 and is connected at one end to said lever 200 and at the other end to the bearing 204 on the bottom of the plate or table 185 wherein such stud is journaled, such spring tending normally to rotate the stud and thus disk 194 in a counter-clockwise direction, as viewed in Figs. 23 and 24, whereby the three guides 190 are moved inwardly. However, oscillation of tubular shaft 181 in a counter-clockwise direction to deliver a sheet from the platen 50 onto the table 185, as hereinbefore described, will at the same time serve, through the medium of the connections between said shaft and the guides 190, to move said guides outwardly from their normal positions as determined by the setting of the clamps 181 on rods 192. A sheet upon being released by the delivery device may accordingly settle down freely on the table or on the stack of sheets previously accumulated thereon; however, incidentally to the next clockwise swing of the delivery device to pick up a fresh sheet from the platen, the three guides 190 will be moved inwardly and thus shift the last deposited sheet into predetermined position with respect to the table.

Tubular shaft 181 is supported in brackets 205 attached to the adjacent side frame of the press in much the same way as the two telescoping vertical tubular shafts 5 and 10 are attached to the opposite side of the press, said shaft 181 being both oscillatory and vertically reciprocable in the bearings thus provided, as will be understood. For the purpose of imparting such oscillatory and vertically reciprocable movements to shaft 181, means similar to those employed with shafts 5 and 10 are utilized. Thus (see Fig. 22), said shaft is provided near its lower end with an elongated pinion 206 that is adapted to remain in mesh, despite the vertical reciprocatory movement of the shaft, with a transversely reciprocable rack 207. The latter is carried by two parallel links 208 from the side frame of the press and is actuated by means of a roller 209 on its forward end that engages with a laterally grooved cam 210 mounted on the same shaft 111 that carries the cams whereby the sheet feeding device and associated mechanisms are operated. Adjacent said cam 210 is another cam 211 wherewith a roller 212 on one end of a bell crank lever 213 engages, the other arm of said lever being provided with a fork 214 that engages with a circumferentially grooved collar 215 fixed to said shaft 181. The cams 210 and 211 will of course be so laid out as to produce a resultant swinging and rising or falling movement of delivery arm extension 183 so as not only to pick up and transfer a sheet from the platen to the delivery table, in the fashion hereinbefore described, but also avoid interfering with the movement of the sheet feeding device which must necessarily be, at least in the major part, simultaneous with such movement of the delivery device. In other words, a fresh sheet has to be picked up by the latter from table 50 and started towards the platen at the same time that the previously printed sheet is being picked up from the latter and started toward the delivery table 185.

Shaft 181 is provided at its lower end with a hose connection 216 whereby it may be connected with a suitable suction producing device. It will be noted that a similar hose connection 217 is provided at the lower end of the tubular shaft 5 that carries the sheet feeding device wherein suction is likewise utilized in order to pick up and transfer a sheet of paper from the feed table to the platen; while, as explained in the course of the description of the sheet separating device that is associated with the feed table, the suction line requires to be connected with pipe 143. In the case of the air blast device, on the contrary, air under pressure requires to be supplied to pipe 164.

While the air suction and air pressure for the four connections in question may be de-

rived from separate sources, or from sources entirely without the feeding and delivery mechanism proper, in order to make the latter self-contained in these respects, I provide 5 a rotary pump 220 which may be directly connected with the press so as to be operated therefrom, although if preferred such pump may be independently driven as by means of an electric motor. As shown, said pump is 10 mounted on the same side of the press as the vertical telescoping tubular shafts 5 and 10 and immediately to the rear of the same. The discharge 221 from the pump is directly connected with the aforesaid line 164 that 15 leads to the air blast device associated with the feed table, the volume of air actually delivered to such device being in the first place rendered intermittent by the reciprocable sleeve 166 and in the second place regulated to suit the demands of the particular 20 case by adjustment of sleeve 160 on tube 155. The intake or suction 222 of pump 220 is provided with a regulating valve 223 whereby a predetermined degree of vacuum 25 is at all times maintained in the main hose connection 224 that leads to such suction intake and in the several ducts whereby such main duct is connected with tubular shafts 5 and 181 and with the pipe 143 that leads to 30 the separating device. As best shown in Fig. 2, the ducts 225, 226 and 227, that lead to such shafts and pipe respectively, are connected at their opposite ends with a series of 35 three similar valves 228 mounted in front and closely adjacent to main operating shaft 111, the main suction duct 224 that leads to the intake of the pump having a common connection 229 with said valves.

The detail construction of the latter is 40 shown in Fig. 16 where it will be seen that a chamber 230 in the valve body 231 forms a continuation of connection 229. Reciprocably mounted in such body is a hollow cylindrical valve 232 that is normally depressed 45 into the position shown in said figure by the action of a coil spring 233 on a lever 234 connected with the upper end of said valve. Said lever, however, is provided intermediate of its ends with a roller 235 that contacts with a disk cam 236 on shaft 111 whereby at stated times the valve will be raised. In such depressed position a port 237 in the valve communicates with chamber 230, thereby placing the interior of the valve, as well 55 as the tubular extension 238 of the valve body, wherewith the interior of such valve freely communicates, under the same vacuum as exists in vacuum line 224. Conversely when the valve is raised, a slit-like 60 port 239 near its upper end will lie clear of the valve body and so open the interior of such valve, and thus of valve body extension 238, to the atmosphere. Port 237 being then closed, the vacuum will be relieved in the particular device connected with the valve, e. g.,

the sheet separating device, through the duct 227 which leads to the particular valve illustrated in Fig. 16, just as such vacuum is applied in the first described position of the valve.

The condition may arise that due to failure of such sheet separating device, or one of the other devices equipped with suction tips, to properly pick up a sheet of paper, the line to such device will not be sealed at its outer end and in that event the vacuum throughout the system would be relieved so as to render all such devices inoperative. In order to avoid this contingency, I provide a supplemental sealing valve 240 in the valve body extension 238, such valve like the main valve 232 being of hollow cylindrical form and provided with lateral ports 241 that are adapted in the lower position of the valve to permit free communication between the main valve body and the duct connected with the lower end of such body extension. To this end radial projections 242 are provided on the lower end of such valve 240 so as to support such valve on a ledge 243. However, should the sucker tips of the device connected with such valve body fail to be sealed when the main valve 232 is lowered to bring port 237 into register with suction chamber 230, the current of air drawn through the valve body is sufficient to raise said supplemental valve 240 into sealing position, as shown in dotted outline in Fig. 16. The ports 241 then being closed, vacuum will be maintained in chamber 230, despite the non-sealing of the sucker tips in the particular device in question.

The operation of the several devices composing my improved sheet feeding and delivery mechanism has been sufficiently explained in connection with the description of such devices and associated parts. It hence remains only to set forth the manner in which the movements of these devices are correlated in the general operation of the mechanism.

Assuming a stack of blank sheets to be in proper place on the table 50, as determined by the guides 152, so that when a sheet is transferred from such stack to the platen it will correctly register thereon, the table elevating mechanism will be manually operated to raise the top of the stack until the sucker tips 135 of the sheet separating mechanism contact with such stack. The latter may in fact be raised until the oscillatory frame 75, which carries such sucker tips, is in turn raised to lift set screw 92 out of contact with plate 91 in the depressed position of plunger 90.

The sucker tips of the sheet feeding mechanism being adjusted to properly contact with the topmost sheet of the stack and the rear end of slide-actuating lever 40 of such device being adjusted to shift the position of such

tips during the transfer of the sheet to the platen, if this be necessary, and the sheet delivery mechanism being adjusted as hereinbefore described, the following sequence of operations will occur. The particular valve 238 connected with the separator tips 135 will connect the latter with the suction line so that the topmost sheet is caused to adhere to such tips. At the same time the air blast nozzle 150 with associated brush 170 is oscillated towards the stack and slide valve 166 moved to closed position so that a blast of air is discharged against the edges of the upper sheets of the stack. Thereupon the sucker tips 135 are rocked from the position shown diagrammatically in Fig. 28 to that shown in Fig. 29, with the result that the edge of the topmost sheet is tilted upwardly. Next by a reverse rocking movement of the tips, the latter are raised to the position shown in Fig. 30 which will be effective to substantially free the topmost sheet from the one beneath. At this juncture suction is applied to the sucker tips 25 of the sheet feeding device and the separator tips are bodily raised a trifle higher, as shown in Fig. 31, so as to bring the sheet attached thereto into contact with such tips 25 to which the sheet becomes attached in turn. The suction on the separator tips being simultaneously relieved, the swinging movement of the feeding device may begin immediately and the sheet is carried thereby through an arcuate path to its place on the platen where it is brought accurately in register with the usual locating devices. The suction on tips 25 is then instantly relieved and the feed device begins its return movement to position over the stack. While a fresh sheet is thus being transferred from the stack to the platen, the delivery device has picked up the previously printed sheet on such platen and deposited the same on table 185 where such sheet is properly located by the means provided for the purpose to form a compact stack.

Whenever, due to the removal of successive sheets from the top of the stack on table 50, the upper level of such stack falls sufficiently to permit set screw 92 to rest on plate 91 in the depressed position of plunger 90, the additional weight of oscillatory frame 75 and the parts carried thereby will rock the pawl detent or shroud member 105 out of the path of pawl 66, with the result that the table is elevated until such screw no longer contacts with the plate, and this operation will be repeated until the stack is exhausted.

From the foregoing description it will be seen that the operation both of the sheet feeding and delivery devices is wholly automatic in character. Furthermore the several devices may be readily adjusted so as to insure accurate positioning of the sheet on the platen and the removal of same without interference with the sheet feeding device to the stack

on the delivery table. The several devices are moreover arranged for attachment to a platen press of standard construction and in such a way as to permit convenient access to the platen without removal of any of said devices. All the parts of the latter which may require adjustment, in order to set the mechanism for use with sheets of different sizes or thickness, are readily accessible. Finally, none of the parts require to be moved at excessive speeds so that such parts may be of relatively light construction and the power required to operate the mechanism is accordingly reduced to a minimum.

Other modes of applying the principle of my invention may be employed instead of the one explained, change being made as regards the mechanism herein disclosed, provided the means stated by any of the following claims or the equivalent of such stated means be employed.

I therefore particularly point out and particularly claim as my invention:—

1. In mechanism of the character described, the combination with a suitable support; of a member oscillatorily mounted thereon; a second member oscillatorily mounted on said first member about an axis removed from the latter's axis of oscillation; a sheet engaging and moving device attached to said second member so as to be movable transversely of its axis; and means adapted to shift the position of said device on said second member incidentally to oscillation of the latter.

2. In mechanism of the character described, the combination with a suitable support; of a member oscillatorily mounted thereon; a second member oscillatorily mounted on said first member about an axis removed from the latter's axis of oscillation; a sheet engaging and moving device attached to said second member so as to be movable transversely of its axis; and means adapted to shift the position of said device on said second member incidentally to oscillation of the latter, said means being adjustable to vary the amount of shifting movement thus imparted to said device.

3. In mechanism of the character described, the combination with a suitable support; of an arm oscillatorily mounted thereon; a second arm oscillatorily mounted on said first arm about an axis removed from the latter's axis of oscillation; a suction member longitudinally movably attached to said second arm; and means adapted to shift the position of said member on said second arm incidentally to oscillation of the latter, said means being adjustable to change the direction of shifting movement thus imparted to said member.

4. In mechanism of the character described, the combination with a suitable support; of an arm oscillatorily mounted there-

on; a second arm oscillatorily mounted on said first arm about an axis removed from the latter's axis of oscillation; a suction member longitudinally movably attached to said second arm; and means adapted to shift the position of said member on said second arm incidentally to oscillation of the latter, said means being adjustable to change the direction and vary the amount of shifting movement thus imparted to said member.

5. In mechanism of the character described, the combination with a suitable support; of an arm oscillatorily mounted thereon; a second arm oscillatorily mounted on said first arm about an axis removed from the latter's axis of oscillation; a suction member carried by said second arm; and adjustable connections between said support and said second arm whereby the latter is oscillated about its axis upon oscillation of said first arm about its axis.

6. In mechanism of the character described, the combination with a suitable support; of an arm oscillatorily mounted thereon; a second arm oscillatorily mounted on said first arm about an axis removed from the latter's axis of oscillation; a suction member carried by said second arm; and link and lever connections between said support and said second arm whereby the latter is oscillated about its axis upon oscillation of said first arm about its axis, said connections including an eccentric adjustment for varying the movement of said second arm.

35. 7. In mechanism of the character described, the combination with a suitable support; of an arm oscillatorily mounted thereon; a second arm oscillatorily mounted on said first arm about an axis removed from the latter's axis of oscillation; a slide movable longitudinally of said second arm; a transverse bar carried by said slide; and a plurality of suction tips secured to said bar in longitudinally spaced relation.

45. 8. In mechanism of the character described, the combination with a suitable support; of an arm oscillatorily mounted thereon; a second arm oscillatorily mounted on said first arm about an axis removed from the latter's axis of oscillation; a slide movable longitudinally of said second arm; a transverse bar carried by said slide; and a plurality of suction tips adjustably secured to said bar.

55. 9. In mechanism of the character described, the combination with a suitable support; of an arm oscillatorily mounted thereon; a second arm oscillatorily mounted on said first arm about an axis removed from the latter's axis of oscillation; a slide movable longitudinally of said second arm; a transverse bar carried by said slide; and means adapted to shift said slide incidentally to oscillation of said second arm, said means including a bracket fixed to said first arm and

a link connecting said bracket with said slide.

10. In mechanism of the character described, the combination with a suitable support; of an arm oscillatorily mounted thereon; a second arm oscillatorily mounted on said first arm about an axis removed from the latter's axis of oscillation; a slide movable longitudinally of said second arm; a transverse bar carried by said slide; and means adapted to shift said slide incidentally to oscillation of said second arm, said means including a bracket fixed to said first arm and a link adjustably pivotally secured at one end to said bracket and at its other end pivotally connected to said slide.

11. In mechanism of the character described, the combination with a suitable support; of an arm oscillatorily mounted thereon; a second arm oscillatorily mounted on said first arm about an axis removed from the latter's axis of oscillation; a slide movable longitudinally of said second arm; a transverse bar carried by said slide; and means adapted to shift said slide incidentally to oscillation of said second arm, said means including a bracket fixed to said first arm and provided with an arcuate slot, and a link adjustably pivotally secured at one end to such slot and at its other end pivotally connected to said slide, such slot having as its center a point on said link.

12. In mechanism of the character described, the combination with a suitable support; of an arm oscillatorily mounted thereon; a second arm oscillatorily mounted on said first arm about an axis removed from the latter's axis of oscillation; a slide movable longitudinally of said second arm; a transverse bar carried by said slide; and means adapted to shift said slide incidentally to oscillation of said second arm, said means including a bracket fixed to said first arm and provided with an arcuate slot, and a link adjustably pivotally secured at one end to such slot and at its other end pivotally connected to said slide, such slot intersecting the axis of oscillation of said second arm, extending both above and below such axis and having as its center a point on said link.

13. The combination with a table adapted to support a stack of sheets, of a sheet-feeding device movable to and from a position over such stack and adjacent one edge thereof, such device including means adapted to engage and hold the sheet being carried, and a device located over such stack and provided with suction tips adapted to contact with the topmost sheet of such stack adjacent the edge in question, said device while thus in contact with such sheet being oscillatory about an axis approximately parallel with such edge and being also movable vertically with respect to said table, whereby such topmost sheet may be separated from the others and

lifted into position to be picked up by said feeding device.

14. The combination with a table adapted to support a stack of sheets, of a sheet-feeding device movable to and from a position over such stack and adjacent one edge thereof, such device including suction tips adapted to hold the sheet being carried, a device located over such stack and adapted to separate the topmost sheet along the edge in question from the others preparatory to its being picked up by said feeding device, said separating device being bodily movable towards and from the stack incidentally to the removal of successive sheets, and means for automatically elevating said table, operation of said means being controlled by said sheet separating device.

15. The combination with a table adapted to support a stack of sheets, of a sheet-feeding device movable to and from a position over such stack and adjacent one edge thereof, such device including suction tips adapted to hold the sheet being carried, a device located over such stack and adapted to separate the topmost sheet along the edge in question from the others preparatory to its being picked up by said feeding device, and means adapted simultaneously to direct a blast of air against the corresponding side of the stack.

16. The combination with a table adapted to support a stack of sheets, of a sheet-feeding device movable to and from a position over such stack and adjacent one edge thereof, such device including suction tips adapted to hold the sheet being carried, a device located over such stack and adapted to separate the topmost sheet along the edge in question from the others preparatory to its being picked up by said feeding device, and a brush adapted simultaneously to press lightly against the corresponding side of the stack.

17. The combination with a table adapted to support a stack of sheets, of a sheet-feeding device movable to and from a position over such stack and adjacent one edge thereof, such device including suction tips adapted to hold the sheet being carried, an oscillatory frame at one end of said table, a bar oscillatorily attached to the free end of said frame and extending across said table, and suction tips carried by said bar in longitudinally spaced relation and adapted to contact with the topmost sheet of such stack adjacent the edge in question, whereby oscillation of said bar will separate such topmost sheet from the others and upward oscillation of said frame thereupon will serve to lift such sheet into position to be picked up by said feeding device.

18. The combination with a table adapted to support a stack of sheets, of a sheet-feeding device movable to and from a position

over such stack and adjacent one edge thereof, such device including suction tips adapted to hold the sheet being carried, an oscillatory frame at one end of said table, a bar oscillatorily attached to the free end of said frame and extending across said table, suction tips carried by said bar in longitudinally spaced relation and adapted to contact with the topmost sheet of such stack adjacent the edge in question, whereby oscillation of said bar will separate such topmost sheet from the others and upward oscillation of said frame thereupon will serve to lift such sheet into position to be picked up by said feeding device, means normally positioning said bar about its axis of oscillation, and means adapted positively to oscillate same at predetermined intervals.

19. The combination with a table adapted to support a stack of sheets, of a sheet-feeding device movable to and from a position over such stack and adjacent one edge thereof, such device including suction tips adapted to hold the sheet being carried, an oscillatory frame at one end of said table, a bar oscillatorily attached to the free end of said frame and extending across said table, suction tips carried by said bar in longitudinally spaced relation and adapted to contact with the topmost sheet of such stack adjacent the edge in question, whereby oscillation of said bar will separate such topmost sheet from the others and upward oscillation of said frame thereupon will serve to lift such sheet into position to be picked up by said feeding device, and means adapted positively thus to oscillate said frame upwardly, downward oscillation thereof being limited by contact of the suction tips carried thereby with the stack.

20. The combination with a table adapted to support a stack of sheets, of a sheet-feeding device movable to and from a position over such stack and adjacent one edge thereof, such device including suction tips adapted to hold the sheet being carried, an oscillatory frame at one end of said table, a bar oscillatorily attached to the free end of said frame and extending across said table, suction tips carried by said bar in longitudinally spaced relation and adapted to contact with the topmost sheet of such stack adjacent the edge in question, whereby oscillation of said bar will separate such topmost sheet from the others and upward oscillation of said frame thereupon will serve to lift such sheet into position to be picked up by the feeding device, means adapted positively thus to oscillate said frame upwardly, downward oscillation thereof being limited by contact of the suction tips carried thereby with the stack, means normally positioning said bar about its axis of oscillation, and means adapted positively to oscillate same at predetermined intervals.

21. The combination with a table adapted to support a stack of sheets; of a sheet separating device including a frame located adjacent said table and movable in a general vertical direction relatively thereto, and a suction tip carried by said frame and adapted to contact with the top-most sheet of such stack, downward movement of said frame being limited by such contact; and periodically operating means adapted positively to raise said frame.

22. The combination with a table adapted to support a stack of sheets; of a sheet separating device including a frame located adjacent said table and movable in a general vertical direction relatively thereto, and a suction tip carried by said frame and adapted to contact with the top-most sheet of such stack, downward movement of said frame being limited by such contact; a vertically reciprocable member adapted to engage and positively raise said frame; means for elevating said table; and connections between said reciprocable member and means for controlling operation of the latter, whereby such operation is permitted only when the weight of said frame is imposed on said member in its lowermost position.

23. The combination with a table adapted to support a stack of sheets; of a sheet separating device including a vertically oscillatory frame located adjacent said table and a suction tip carried by said frame and adapted to contact with the topmost sheet of such stack, downward oscillation of said frame being limited by such contact, said tip being movable arcuately and also in a rectilinear vertical path; and periodically operating means adapted positively to oscillate said frame upwardly.

24. The combination with a table adapted to support a stack of sheets; of a sheet-feeding device movable to and from a position over such stack and adjacent one edge thereof, such device including suction tips adapted to hold the sheet being carried, a device located over such stack and adapted to separate the topmost sheet along the edge in question from the others preparatory to its being picked up by said feeding device, and a tubular air nozzle directed towards and adapted to discharge a blast of air against the corresponding side of the stack, said nozzle being vertically adjustable relatively to such stack.

25. The combination with a table adapted to support a stack of sheets, of a sheet-feeding device movable to and from a position over such stack and adjacent one edge thereof, such device including suction tips adapted to hold the sheet being carried, a device located over such stack and adapted to separate the topmost sheet along the edge in question from the others preparatory to its being picked up by said feeding device, a tubular air nozzle directed towards and adapted to

discharge a blast of air against the corresponding side of the stack, and a brush carried by said nozzle and having its bristles disposed to contact with such side of the stack.

26. The combination with a table adapted to support a stack of sheets, of a sheet-feeding device movable to and from a position over such stack and adjacent one edge thereof, such device including suction tips adapted to hold the sheet being carried, a device located over such stack and adapted to separate the topmost sheet along the edge in question from the others preparatory to its being picked up by said feeding device, a tubular air nozzle directed towards and adapted to discharge a blast of air against the corresponding side of the stack, and a brush carried by said nozzle and having its bristles disposed to contact with such side of the stack, said nozzle and brush being vertically adjustable relatively to such stack.

27. The combination with a table adapted to support a stack of sheets, of a sheet-feeding device movable to and from a position over such stack and adjacent one edge thereof, such device including suction tips adapted to hold the sheet being carried, a device located over such stack and adapted to separate the topmost sheet along the edge in question from the others preparatory to its being picked up by said feeding device, a tubular air nozzle directed towards and adapted to discharge a blast of air against the corresponding side of the stack, and a brush carried by said nozzle and having its bristles disposed to contact with such side of the stack, said nozzle and brush being movable towards and from such stack.

28. The combination with a table adapted to support a stack of sheets, of a sheet-feeding device movable to and from a position over such stack and adjacent one edge thereof, such device including suction tips adapted to hold the sheet being carried, a device located over such stack and adapted to separate the topmost sheet along the edge in question from the others preparatory to its being picked up by said feeding device, a vertically disposed tube adjacent the corresponding side of the stack, said tube being oscillatory about a transverse axis parallel with such side, a nozzle at the upper end of said tube directed towards the stack, and means adapted to regulate the volume of air passing through said tube to said nozzle.

29. The combination with a table adapted to support a stack of sheets, of a sheet-feeding device movable to and from a position over such stack and adjacent one edge thereof, such device including suction tips adapted to hold the sheet being carried, a device located over such stack and adapted to separate the topmost sheet along the edge in question from the others preparatory to its being picked up by

5 said feeding device, a vertically disposed tube adjacent the corresponding side of the stack, said tube being oscillatory about a transverse axis parallel with such side, a nozzle at the upper end of said tube directed towards the stack, a series of openings in said tube below said nozzle, and a valve slidably secured to said tube and adapted to vary the size of such openings or close same entirely as desired.

10 30. The combination with a table adapted to support a stack of sheets, of a sheet-feeding device movable to and from a position over such stack and adjacent one edge thereof, such device including suction tips adapted to hold the sheet being carried, a device located over such stack and adapted to separate the top-most sheet along the edge in question from the others preparatory to its being picked up by said feeding device, a tubular air nozzle directed towards and adapted to discharge a blast of air against the corresponding side of the stack, a duct connecting said nozzle with a substantially constant air-pressure supply, and means adapted periodically to vent the 25 air from said duct before it reaches said nozzle.

31. The combination with a table adapted to support a stack of sheets, of a sheet-feeding device movable to and from a position over such stack and adjacent one edge thereof, such device including suction tips adapted to hold the sheet being carried, a device located over such stack and adapted to separate the top-most sheet along the edge in question from the others preparatory to its being picked up by said feeding device, a tubular air nozzle directed towards and adapted to discharge a blast of air against the corresponding side of the stack, a duct connecting said nozzle with a substantially constant air-pressure supply, and means adapted periodically to vent the air from said duct before it reaches said nozzle, said last-named means operating in unison with said sheet-separating device.

45 32. In mechanism of the character described, the combination with a plurality of independently movable suction tips respectively adapted to engage a sheet of paper or the like; of a main suction line having branches connected with the several tips; and means in each of said branches adapted automatically to seal the same in case of failure of a sheet to seal the corresponding tip, said means being thus operable by the current of air thereupon drawn through said branch.

33. In mechanism of the character described, the combination with a plurality of independently movable suction tips respectively adapted to engage a sheet of paper or the like; of a main suction line having branches connected with the several tips; a valve in each of said branches adapted in one position to apply suction to the corresponding tip and in another position to open said tip to

atmosphere; and a second valve in each branch adapted automatically to close the suction of said tip in case of failure of a sheet to seal the corresponding tip.

34. In mechanism of the character described, the combination with a plurality of independently movable suction tips respectively adapted to engage a sheet of paper or the like; of a main suction line having branches connected with the several tips; a valve in each of said branches adapted in one position to apply suction to the corresponding tip and in another position to open said tip to atmosphere; and a second valve in each branch adapted automatically to close the suction to said tip in case of failure of a sheet to seal the corresponding tip, said second valve being thus operable by the current of air thereupon drawn through said branch.

Signed by me this 11th day of October, 1923. 65
CHARLES F. ROOT.
